UNITED STATES PATENT OFFICE.

WILLIAM A. MERRALLS, OF KANSAS CITY, MISSOURI.

GOLD-SEPARATOR.

SPECIFICATION forming part of Letters Patent No. 391,421, dated October 23, 1888.

Application filed July 13, 1888. Serial No. 279,815. (No model.)

To all whom it may concern:

Be it known that I, WILLIAM A. MERRALLS, of Kansas City, Jackson county, Missouri, have invented certain new and useful Improvements 5 in Gold-Separators, of which the following is a full, clear, and exact description, reference being had to the accompanying drawings, forming a part hereof.

This invention relates to an improved apparatus for extracting gold from placer mines; and it consists in the means and devices hereinafter set forth, and pointed out in the claims.

In the drawings, which illustrate the manner of carrying out my invention, Figure 1 exhibits a side elevation of a rotary settling-tank and a series of settling-boxes which I use. Fig. 2 is a plan view of the devices shown in Fig. 1. Fig. 3 is a transverse sectional view 20 through a mercury-trap. Fig. 4 is a detail elevation of a faucet used upon the rotary settling-tanks. Fig. 5 is a sectional view of the same on line *y y*. Fig. 6 is an end view of the two rotary settling-tanks, looking toward the same from the left hand of Fig. 2; and Fig. 7 25 is a longitudinal section through one of said settling-tanks.

The purpose of my invention is to extract the fine and coarse gold from placer ground, which usually consists in bowlders, gravel, sand, &c., among which is a certain amount of fine and coarse gold, which is of such nature that it will float on water with a current, (and sometimes without a current,) and being coated with oxides it will not amalgamate, but will 30 pass over amalgamated plates or a body of mercury without being taken up by it.

By means of the apparatus presently described the bowlders, gravel, and sand (except some of the very finest sand) are gotten 35 rid of, and only a residuum of fine sand, gold, and water is left for final treatment.

With this end in view my invention consists in the construction and combination of parts hereinafter described and claimed.

40 In carrying out my invention I employ a series of rotary screens, A, which are located one below the other, so that the material from one will be discharged into the next succeeding one, the successive screens being placed in 45 successively lower planes and their mesh successively finer. Below the lowest screen I have a pair of cylinders, which I may term

"revolving settling-tanks," into which the fine gravel and gold are discharged. These settling-cylinders have a double function—viz., 55 that of a stationary settling-chamber and a revolving mixing-chamber, within which the material undergoes a certain chemical treatment, as will be presently described. Hand-holes *g* are provided in opposite ends of said 60 cylinders, through which they are filled and emptied, respectively. A series of faucets or valves, 22, are located on corresponding ends of said cylinders, by means of which the surplus water may be drawn off when desired. 65 The cylinders are supported upon friction-rollers 56, which are arranged beneath them in suitable bearings, and they are also provided with journals 55 at their ends. Of course, however, the arrangement for supporting the 70 cylinders E may be varied. For instance, they may be entirely supported by the journals 55, and the rollers 56 may be dispensed with, and vice versa. A revolving motion is given to the cylinders by means of pulleys 15, 75 mounted on shafts 14, and pinions 13, also mounted on said shafts, which latter mesh with toothed racks 12, which encircle said cylinders at about the middle of their length. After 80 that I employ a number of stationary settling-boxes, F, which are sufficient in number to properly settle any slime that may pass through the settling-cylinders E. The stationary settlers have arranged in them, so as to be near the surface of the liquid which they contain, a number of U-shaped dippers, F'. These are removably located in said boxes at 85 a height that will correspond to the level of the liquid contained therein. The series of stationary settling-boxes are connected together 90 by overflow-troughs I, as shown, so that the liquid may overflow from one to the other.

Some distance below the bottom of the settling-boxes I, and connected to the last one of the series by means of an overflow-pipe, L, I 95 arrange a filter-box, J. These boxes may be filled with a suitable filtering material, such as a lining of canvas and a filling of hay or straw. A pipe, 23, is arranged to carry the water from faucets 22 into filter J. The filtered water is returned to well W, and is used over and over again by pump P. This pump 100 may of course be of any ordinary construction.

A hose, *d*, is connected to pump *P*, and is adapted to be attached to the end 4 of main water-pipe *b*, and thereby supply water to the revolving screens and the several other parts of the apparatus.

Situated beneath or at one side of the revolving settling-cylinders *E*, I employ an amalgamator, *M*, which is of the following construction: There are a number of oppositely-inclined shelves having a drop of a few inches from one to the other. From the last shelf the material drops upon the upper or higher one of a series of amalgamated copper plates, *N*. Mercury-traps *O* separate the ends of said plates, as shown, and the water and slime are adapted to overflow from one mercury-trap to the other. The highest trap has one end extended some distance to form a mercury-well, *R*, which is separated from the main portion of the trap by a partition having an aperture, *R'*, formed in it near the bottom of the well, and which is to be closed by a suitable plug. The bottom 25 of the first trap (shown in plan view in Fig. 5) is inclined toward a faucet, 24, which is located in the end opposite well *R*, for the purpose hereinafter mentioned.

A sprocket-chain, *S*, is provided with suitable buckets and arranged to run over pulleys located in well *R*, and above the top shelf of the amalgamator *M*, so as to lift the mercury contained in the well and deposit it in a trough, *T*, arranged above the top shelf of the amalgamator. Said trough is provided with a series of perforations, *U*, through which the mercury drops to the top shelf of the amalgamator. The mercury-elevator or sprocket-chain *S* is arranged to be run by means of a belt-pulley, 75, carried upon the shaft of one of its driving-wheels, or it may be run in any other suitable way. The purpose of this arrangement of rotary screens is to hold back as much of the sand as possible, and to let only the water and fine gold pass on for further treatment. Such material, after passing through the series of screens and curved aprons, drops upon one of the troughs *G*, and is conducted through one of the hand-holes *g* into one of the rotary settling-cylinders *E*, which, for the time being, is made stationary, and as it is filled up with water and sand and whatever fine gold there is in the material the sand settles to the bottom of the cylinder, and the water, with what fine slime it carries, passes on through the cylinder and out through the hand-hole in its opposite end and through trough *H* into the first of the series of stationary settling-boxes *F*, where it is allowed further time to settle. The water and slime pass from one stationary settling-box to another through troughs *I*, until they issue from the last box of the series, whence they pass down pipe *L* to filter *J*. Should there be any fine gold that has escaped the settling-boxes, it is caught in the filter. The filtered water passes from the filter to well *W*, 65 where it is pumped up into the head of the sluice by pump *P* through hose *d*, and is used over again. The settling-boxes being nearly

full of water and there being some gold so fine as to float on the surface, I introduce one or more skimmers or dippers, *F'*, which are substantially U-shaped in cross-section, and which are arranged in said tanks so as to intercept the surface current of the liquid, the fine gold and slime settling into the hollow or trough-shaped portion of said skimmers. The skimmers may be removed from their normal position and cleaned whenever necessary. Their contents should be emptied into one of the cylinders *E* before it is ready for amalgamation. As soon as sufficient material for a charge has settled in one of the cylinders *E* (while stationary) a gate or valve, *X*, is changed so as to carry the material into the other cylinder, and so on, as before described. The fine sand and gold and the pulp that has settled in the cylinder are now ready for treatment and for a course of amalgamation. The hand-holes in either end of the cylinder are closed and a tight joint made, and the cylinder is allowed to make one or more revolutions 80 for the purpose of leveling the pulp inside, when it is again stopped and the surplus water is allowed to run out through faucets 22, whence it flows through pipe 23 to the filter *J*, thus saving anything of value that might have 95 gone out with it. After the water is drained off, the cylinder is turned until the large faucet *E''* in its side is up, when a chemical mixture (which forms no part of my present invention, and hence need not be described here) 100 is introduced, and the cylinder is started and allowed to revolve for about an hour, when the fine gold that is in the pulp will have been chemically coated with a film of mercury in place of the coating of oxide which it previously carried. As is well known, this oxide coating would have greatly retarded the process of amalgamation; but, the coating being now removed, the course of amalgamation will be very thorough and complete. The cylinder should now be stopped with faucet *E''* downward, as shown more clearly in Fig. 7. A hose is now attached to a suitable coupling, *e'*, formed upon body of faucet *E''*, and a small stream of water (enough to make the pulp 115 flow freely down the inclined shelves of the amalgamator) is allowed to enter the said faucet through said hose. Faucet *E''* should now be opened by means of handle *f*. The amount of opening given said faucet should 120 be regulated according to circumstances, and as the water and pulp flow from the mouth of the faucet they fall upon the top shelf of the amalgamator, where the pulp will be mixed with mercury which has been lifted and distributed, as before described. The mercury and pulp thus mixed flow down the shelves of the amalgamator to the first and highest of the amalgamated copper plates *N*, and a portion of the mercury is retained on said copper 130 plate, and what is not retained slides down into the first mercury-trap *O*, to be elevated by the sprocket-chain and used over again. Sprinkling-pipes are arranged over the several mer-

cury-traps, so as to shower just enough water upon the pulp to keep it loose and light as it passes from the copper plates into the traps. The mercury sinks down through the soft pulp into the trap, and the pulp passes on to the next plate, and so on. Whenever necessary, the mercury in the main portion of the traps is taken out by means of stop-cock 24 or a suitable plug, the excess of mercury being returned to the well R. Only the excess is returned to the well, the mixture of gold and mercury being removed from the trap and retorted in the ordinary way.

The amalgamated copper plates N should be cleaned off every day, or whenever necessary, and the mercury should be strained and the hard amalgam retorted.

Having thus described my invention, what I claim is—

1. In a gold-separator, the rotary imperforate cylinder having a hand-hole and valve in each head near the periphery for receiving the pulp and permitting the escape of float gold,

a valved peripheral discharge for the heavy concentrates, and discharge-cocks in one end 25 at different distances from the periphery for the escape of the intermediate grades, substantially as described.

2. In a gold-separator, the combination of the rotary imperforate cylinder having a hand-hole and valve in each head near the periphery for receiving the pulp and permitting the escape 30 of float gold, a valved peripheral discharge for the heavy concentrates, and discharge-cocks in one end at different distances 35 from the periphery for the escape of the intermediate grades, and a stationary settling-box, into which the overflow from said cylinder is discharged, substantially as described.

In testimony whereof I affix my signature in 40 presence of two witnesses.

WILLIAM A. MERRALLS.
